UNITED STATES PATENT OFFICE.

PHILIP M. HOWSE, OF NASHVILLE, TENNESSEE, ASSIGNOR TO HOL-FAST BEDLOCK COMPANY, OF NASHVILLE, TENNESSEE, A CORPORATION OF TENNESSEE.

SIDE-RAIL FASTENER FOR BEDS.

Application filed June 8, 1927. Serial No. 197,395.

This invention relates to furniture and more particularly to a fastener by means of which a side rail of a bed may be firmly but releasably secured to a bed post. The 5 present invention is an improvement over a somewhat similar fastener constituting the subject-matter of my copending application filed May 5, 1927, Serial No. 189,055.

One object of the invention is to provide 10 a fastener which may be readily applied to the inner face of the side rail of a bed and serve not only as means to connect the side rail with a bed post but also as a corner brace at the intersection of the side rail with the 15 bed post.

Another object of the invention is to provide improved means to pivotally mount levers forming part of the fastener upon a rail engaging plate and prevent the levers from 20 working loose upon a pivot and moving out of proper relation to each other.

Another object of the invention is to so dispose the levers that they will bear against a side flange projecting from the attaching 25 plate and thereby provide means to brace the levers and prevent the pivot pin of the levers from being subjected to shearing strain when anchoring arms carried by the levers are moved into tight binding engagement 30 with abutment pins carried by a bed post.

Another object of the invention is to provide the levers with companion racks adapted to interlock and securely but releasably retain the levers in a set position 35 with the anchoring arms of the fastener in tight engagement with abutment pins carried by a bed post.

The invention is illustrated in the accompanying drawing, wherein:

Figure 1 is a view showing the improved fastener in side elevation with its anchoring arms extending into a pocket formed in a bed post, a portion of which is shown in 45 vertical section;

Fig. 2 is a view showing the corner post and side rail of a bed in section and the improved fastener in top plan;

Fig. 3 is a sectional view taken on the line 50 3—3 of Fig. 1;

Fig. 4 is a fragmentary longitudinal sectional view through the levers when interlocked;

Fig. 5 is a transverse sectional view

through the levers taken on the line 5—5 of Fig. 4, and.

Fig. 6 is a view of a block employed when storing or shipping a pair of bed rails.

The rail fastener constituting the subject-matter of this invention is employed to connect a side rail 1 of a bed to a corner post 2 having a pocket 3 formed therein through which pins 4 extend in vertically spaced relation to each other. The bracket 5 which constitutes the body portion of the fastener 60 is formed of sheet metal and has one end portion bent to form a flange 6 which projects transversely from the side rail, as shown in Fig. 2, when the bracket is applied to the side rail and secured by screws 7 70 passed through openings formed in the bracket. The outer surface of the flange may extend flush with the end face of the bed rail, as shown in Fig. 2, or the rail may be allowed to project slightly beyond the 75 flange in order that a slight inward movement may be imparted to the bed rail when the fastener is tightened.

The levers 8 and 9 are also formed of strong sheet metal and each is stamped to 80 provide a longitudinally extending rib 10 which serves to strengthen the lever and prevent it from being bent by pressure exerted during movement of the levers into and out of an operative position. These 85 levers have their forward end portions disposed one upon the other and formed with registering openings 11 through which a rivet 12 is passed, the rivet being also passed through an opening 13 formed in the plate 90 or bracket 5 and upset, as shown at 14, so that the rivet will be held in place and the two levers pivotally mounted. At their forward ends the levers have arcuate edge faces with the axis of the rivet as their centers, and these arcuate edge faces merge into the flat outer side edges of side extensions 95 15 which project transversely from the levers in opposite directions, as clearly shown in Fig. 1. By referring to this figure, it 100 will be seen that the opening 13 through which the rivet passes is disposed in such spaced relation to the flange 6 that the forward ends of the levers will always bear against the inner surface of the flange. 105 Therefore, the levers will be braced against forward movement and when they are swung about the rivet there will be no dan-

ger of the rivet being subjected to a shearing action which might cause it to be severed. It is also important that the pivotally mounted ends of the levers be retained 5 in proper relation to each other. Therefore, the forward end or hub portion of the lever 8 has been stamped to provide a circular concavo-convex rib 16 which encircles the outer end of the rivet and fits into a similar 10 rib 17 formed in the forward end portion of the lever 9. By referring to Fig. 3, it will be seen that the portion of the plate or bracket 5 immediately surrounding the opening 13 through which the rivet or pivot 15 pin passes is pressed outwardly to form a circular boss 18 encircled by and bearing against the rib 17. Therefore, the two levers will be so interlocked with respect to each other and the boss 18 that they will be 20 prevented from having movement radially of the rivet or pivot pin 12 and wear upon the rivet or walls of the openings through which it passes which might cause the rivet to be loosened.

25 In order to engage the pins 4, I have provided anchoring arms 19 which are pivotally connected with the side extensions 15 of the levers, as shown at 20, and these anchoring arms are slidably passed through slots 21 and terminate in bills 22 at their free ends which extend downwardly from the arms, as shown in Fig. 1, and are intended to engage the pins 4 when the arms are passed into the pocket 3 of the corner post 2. By referring to Fig. 1, it will be seen that when the arms are passed into the pocket 3 they rest upon the pins and by swinging the levers toward each other the side extensions 15 will be moved away from the flange 6 and the anchoring arms drawn 40 outwardly until the bills 22 are moved into tight binding engagement with the pins. Even if the pins are carelessly driven into the corner post out of parallel relation to each other or one closer to the inner end of the pocket than the other, the anchoring arms may still have proper engagement with them as the levers are movable independent of each other and, therefore, the levers and anchoring arms may accommodate themselves to the positions of the two pins.

45 It is desirable to have the levers securely but releasably held in a set position after after being moved to secure the bed rail to the corner post. Therefore, the levers adjacent their free ends have been formed with side extensions 23 and these widened portions of the levers are crimped, as shown at 50 24, to form transversely extending arcuate ribs having teeth 25 cut therein and providing racks adapted to interlock when the levers are swung toward each other a sufficient distance to cause the racks to overlap, as indicated by dotted lines in Fig. 1. In

view of the fact that the teeth of the racks face in opposite directions, the levers may be moved toward each other and will be prevented from having retrograde movement until the levers are sprung apart a 70 sufficient distance to release the teeth from interlocking engagement with each other. By this arrangement the levers may be very easily and quickly moved to a locking position by merely forcing them toward each other and may be easily released when it is desired to remove a bed rail but will not be liable to accidentally slip out of a set position. Therefore, a side rail of a bed may be 75 very securely secured to a bed post and will be prevented from being accidentally attached from the post but may be very easily released when it is desired to take the bed apart. It should also be noted that since the flange 6 bears against the post the bracket 80 constitutes a corner brace for the post and side rail and holds them in proper relation to each other.

85 In Fig. 6, there has been shown a block 26 employed when storing or shipping bed rails. This block is formed with slots 27 corresponding to the slots in the bed posts and crossed by pins 28. When the bed rails are to be shipped or stored, they are disposed with their polished faces in facing but 90 spaced relation to each other and the anchoring arms of their fasteners fitted into the slots of the blocks and levers adjusted to firmly engage the arms with the pins. Companion rails will then be joined and 95 can be shipped or stored without danger of them becoming separated or their polished surfaces scratched. Therefore, crating the rails will be unnecessary.

100 Having thus described the invention, I claim:

1. A bed rail fastener comprising a body adapted to be secured against a bed rail and having a flange at one end to bear against a bed post and formed with slots, levers disposed one against the other and at one end pivoted to said body about a common pivot, the pivoted ends of said levers having arcuate edges bearing against said flange, anchors pivoted to said levers and projecting from said flange, and the levers being formed with side extensions adjacent their free ends and stamped to form racks extending transversely across said levers and side extensions and having teeth to interlock 110 and releasably retain the levers in a set position.

115 2. A bed rail fastener comprising a body adapted to be secured against a bed rail, levers pivoted to said body one against the other with their free end portions projecting from the body, the portions of the levers projecting from the body being formed with transversely extending arcuate ribs to overlap when the levers are swung toward each 120 130

other and the ribs having teeth facing in opposite directions and adapted to interlock to releasably retain the levers in a set position.

5. 3. A bed rail fastener comprising a body adapted to be secured against a bed rail, levers pivoted to said body one against the other with their free end portions projecting from the marginal edge of the body, 10 the portions of the levers projecting from the body having portions crimped to provide transversely extending arcuate ribs of a concavo-convex formation in cross section and adapted to contact in overlapping relation to each other when the levers are swung 15 towards each other and having their contacting surfaces formed with teeth facing in opposite directions and adapted to interlock and releasably hold the levers in a set position.

20 4. A bed rail fastener comprising a body adapted to be secured against a bed rail, levers having end portions disposed one against the other and one bearing against 25 the outer face of said body, and a pivot extending through registering openings in said body and levers, portions of the levers around the pivot being formed with annular concavo-convex ribs encircling the pivot 30 and fitting one within the other and the portion of the body about the pivot being formed with an outstanding boss encircled by the rib of the inner lever.

35 5. A bed rail fastener comprising a body adapted to be secured against a bed rail, levers having end portions disposed one against the other and one bearing against the outer face of said body, and a pivot extending through registering openings in 40 said body and levers, a portion of the body about the opening therein being pressed outwardly to form a boss and portions of the levers being pressed inwardly to form concavo-convex ribs encircling the openings 45 in the levers and received one within the other, the rib of the inner lever encircling said boss and preventing movement of the levers radially of the pivot.

50 6. A bed rail fastener comprising a body adapted to be secured against a bed rail, levers having end portions disposed one against the other and one bearing against said body, a pivot connecting said levers with said body, and means to effect inter-

locking engagement between the levers and 55 body and prevent movement of the levers radially of the pivot.

7. A bed rail fastener comprising a body adapted to be secured against a bed rail and having a flange at one end to bear against 60 a bed post and formed with vertically spaced slots, levers pivoted to said body one against the other about a common pivot and having their marginal edge faces bearing against said flange between the slots formed 65 therein, anchors pivoted one to each of said levers and projecting through adjacent slots and retractable by moving the levers in opposite directions, and means to releasably retain the levers in a set position. 70

8. A bed rail fastener comprising a body adapted to be secured against a bed rail and having a flange at one end to bear against 75 a bed post, the flange being formed with vertically spaced slots, levers pivoted to said body one against the other and having their pivotally mounted ends disposed about a common pivot and bearing against said flange between the slots and provided with side extensions extending in opposite directions and each overlapping an adjacent slot, and anchoring arms pivoted one to each of the side extensions of said levers and projecting through the slots formed in said flange and retractable by moving the levers 85 in opposite directions.

9. A bed rail fastener comprising a body adapted to be secured against a bed rail and having a flange at one end to bear against 90 a bed post and formed with vertically spaced slots, levers disposed one against the other and having hub portions at one end bearing against said flange between the slots formed therein and formed with side extensions projecting one upwardly and the other 95 downwardly and each extending across an adjacent slot in the flange, a pivot passed through the body and hubs, anchoring arms each pivoted to a side extension of a companion lever and slidably passed through an adjacent slot, the anchoring arms being adapted to be retracted by moving the levers 100 in opposite directions, and means to releasably retain the levers in a set position. 105

In testimony whereof I affix my signature.

PHILIP M. HOWSE. [L.S.]
